UNITED STATES PATENT OFFICE

ALBERT L. STEMWEDEL, OF CHICAGO, ILLINOIS, ASSIGNOR TO FEE AND STEMWEDEL INC., OF CHICAGO, ILLINOIS

DESIGN FOR AN INDICATOR

Application filed March 23, 1933. Serial No. 47,553. Term of patent 3½ years.

To all whom it may concern:

Be it known that I, ALBERT L. STEMWEDEL, a citizen of the United States, residing at 221 W. Chicago Ave., Chicago, in the county of Cook and State of Illinois, have invented a new, original, and ornamental Design for an Indicator, of which the following is a specification, reference being had to the accompanying drawing, forming part thereof.

Fig. 1 is a front elevational view of the indicator showing my new design.

Fig. 2 is a side elevational view of the indicator.

I claim:

The ornamental design for an indicator, as shown.

In witness whereof, I hereunto subscribe my name this 8th day of April, 1933.

ALBERT L. STEMWEDEL.
